UNITED STATES PATENT OFFICE

148,800

DESIGN FOR AN AERONAUTICAL TRAINING DEVICE

Gordon Laughead, Grand Haven, Mich., assignor
to Gordon Laughead Company, Grand Haven,
Mich.

Application September 19, 1946, Serial No. 133,430

Term of patent 7 years

(Cl. D71—1)

To all whom it may concern:

Be it known that I, Gordon Laughead, a citizen of the United States, residing at Grand Haven, county of Ottawa, State of Michigan, have invented a new, original, and ornamental Design for an Aeronautical Training Device, of which the following is a specification, reference being had to the accompanying drawing, forming a part thereof.

Fig. 1 is a perspective view of an aeronautical training device showing my new design;

Fig. 2 is a top plan view; and

Fig. 3 is an end elevational view.

I claim:

The ornamental design for an aeronautical training device, substantially as shown.
GORDON LAUGHEAD.
